UNITED STATES PATENT OFFICE.

JAMES D. HUMPHREY AND JOSEPH FRENCH, OF TOWANDA, PENNSYLVANIA.

STAMPING AND NUMBERING MACHINE.

SPECIFICATION forming part of Letters Patent No. 660,512, dated October 23, 1900.

Application filed June 15, 1898. Serial No. 683,498. (No model.)

To all whom it may concern:

Be it known that we, JAMES D. HUMPHREY and JOSEPH FRENCH, citizens of the United States, residing at Towanda, in the county of Bradford and State of Pennsylvania, have invented certain new and useful Improvements in Stamping and Numbering Machines; and we do hereby declare the following to be a full, clear, and exact description of the invention, so such as will enable others skilled in the art to which it appertains to make and use the same.

Our invention relates to a power stamping and numbering machine used for imprinting on various articles numbers, letters, and other characters to denote size, style, kind or class, the date of manufacture, a trade-mark, or for the stamping of any other variety of characters that a hand-stamp can be employed to imprint either for designating or for canceling. It is particularly adapted for stamping boots and shoes, although by no means confined in its use to that purpose. As is customary in such machines, the type characters to be printed are formed on the peripheries of disks, which are arranged in series and mounted loosely on a shaft.

Our invention consists in improvements in the operative parts by which the machine is adapted to be driven by any suitable motor, leaving the hands of the operator free to manipulate the articles to be stamped, in a combined treadle and clutch mechanism by which the printing mechanism may be thrown in and out of engagement with the running mechanism and locked from operating, in the construction and arrangement of the type-disks and their casing and the manner of setting and transferring the disks, in the arrangement of the type characters for printing, in the means for operating the type-head to give it an upward and downward throw, in means for indicating to the operator the particular characters set or to be set and also for setting them, in means independent of

the other setting means for adjusting the position of a separate disk bearing a character out of the regular series, in means for giving the inking-pad a swinging parallel movement under the type-disks and a return movement to the rear of the same, in the construction of the pad itself, in means for adjusting the contact of the pad with the type-disks, in a

yielding and self compensating and adjusting platen, in the particular means for operating the several parts, in the construction of an adjustable spring-clamp, in modifications of a few of the parts, and in improvements of some minor details, all as more fully herein-after described and particularly claimed.

Our invention is illustrated in the accompanying drawings, in which—

Figure 1 is a plan; Fig. 2, a side elevation, partly in section, showing the parts in position when the article is stamped; Fig. 3, a side interior view showing the type-head and pad in position when the type is inked and the cam mechanism for operating the type-head; Fig. 4, a detail side elevation of the clutch mechanism; Fig. 5, a sectional view of the type-head on line 5 5 of Fig. 6; Fig. 6, a longitudinal central section of the head; Fig. 7, a vertical upright sectional view of the treadle mechanism and platen when lowered; Fig. 8, a detail of a spring-pawl for holding a type-disk when set; Fig. 9, a detail of the type-disk detent; Fig. 10, a modification in detail of means for adjusting the height of the platen; Fig. 11, a section on line 11 11 of Fig. 6, showing the lever-controlled type-disk; Fig. 12, a front detail view of the type-head, showing index and other characters and the pointer; Fig. 13, a partly-sectional end view of a modification of the index-pointer on the knob of the type-head shaft; Fig. 14, a detail sectional view of means for regulating the pressure and position of the inking-pad relative to the type-disks; Fig. 15, a front view of the modification shown in Fig. 13; Fig. 16, a section on line 16 16 of Fig. 6; Fig. 17, a detail plan of removable type-head cover; Fig. 18, a bottom plan of this cover, and Fig. 19 a detail section of inking-pad and pad-holder.

Referring to the drawings, A is the frame of the machine, adapted to be secured to a table or other suitable support and carrying at one end an adjustable platen A'.

B is the type-head, carrying the type-disks on the end of a vibrating arm C. The construction and operation of both the platen and type-head are herein-after more particularly described. This arm at its inner end is hung on a short rocking shaft c', journaled in standards c², rising from the frame. The arm C is provided with a rearwardly-extend-

ing arm c^3 , which carries a stud, on the end of which is mounted a roller c^4 . The roller face c^4 engages with a cam d on the inner of a cam-wheel D. As the cam-wheel revolves its action by the cam d is to give to the carrying-arm C and type-head an intermittent up-and-down movement. At the deepest point of the cam when the type-head arm is at its lowest position it is extended horizontally over the frame and platen. The cam-wheel D is keyed on a horizontal shaft E, mounted in standards rising from the frame of the machine.

F is a large cog-wheel, also secured on shaft E, opposite the cam, and meshing with a pinion f' , secured on the end of a rear horizontal shaft G, which carries at its opposite end a pulley g , driven by any suitable power.

H is an inking-pad, the specific construction of which, as shown, will be hereinafter described, which is carried at the end of an arm H'. The pad is given a reciprocating movement and is supported and carried in a position at all times directly parallel with the type-head characters when the latter are in position to be inked and printed. The pad and its arm are connected to type-head arm C by swinging link-arms h^2 h^3 . The link h^2 is pivoted at its lower end to a pin h^4 , journaled in one side of the arm H', and its upper end is secured to a short rotating rod c^5 , passed through the arm C. The link h^3 is pivoted at its lower end to a pin h^5 , mounted in a short arm h^6 , extending rearwardly from the pad. At its upper end the link h^3 is formed into a head h^7 of the rotating rod c^5 .

From its pivotal connection with the links the arm H' is bent upward and then extends rearwardly, being formed into a double arm I, comprising two similar sliding members i' and i^2 , the former integral with the type-arm and each having flattened adjacent surfaces to form a close fit and connected by a pin i^3 and spring-pressed collar i^4 at the rear end and a screw-rod i^5 at the other end, a slot for the former of these pins, in which it is adapted to move, being formed in the member i' . Near its rear end the member i' is provided with a lug j , to which is secured the end of a coiled spring j' , seated on the member i' and in the hollow of member i^2 , its opposite end bearing against a shoulder of the latter member, thus tending to force it forward. The screw-rod i^5 projects through a hollow boss i^6 of the member i^2 and a slot of the other member at a forward angle to both and is provided at its lower end with a head bearing against the lower side of member i' and at its upper end with a thumb-nut bearing against the member i^2 . A guide-key j^3 on the upper member slides in a slot or groove j^3 in the lower member. Member i^2 is pivoted at its rear end to a vertical arm K. Turning up the thumb-nut slides backward the member i^2 on i' against the spring, and thus carries slightly forward and upward the arm H', and consequently the swinging pad, nearer the type-

disks, so as to present a new portion of the inking-surface thereto. Turning the nut in the opposite direction releases the coiled 70 spring, which carries forward the member i^2 and the arm back from the type-head, the relative movement of the members being to lengthen and shorten the double arm I.

In order that the pad shall not scrape along 75 the surface of the type when brought in contact therewith, the pad-box is provided with a spring i^9 back of the pad, which permits the pad to yield backward slightly when it strikes the type in its forward and upward 80 movement. This spring is in the cylinder i^{10} and bears against the head on the pad.

The vertical arm K has at its lower end a journal K', mounted on a stud l , rigidly secured to the rear extension c^3 of arm C. To 85 arm K is secured a rod k , extending rearwardly through an apertured lug k' on arm C and surrounded by a coiled spring k^2 , held between said lug and the journal. A roller m^2 , mounted on a stud on arm K, is adapted 90 to engage a cam m , forming part of a bracket m' , keyed on shaft E, by means of which the arm is reciprocated forward and under the type-head to ink the type. The spring k^2 serves to throw the pad-arm backward and 95 the pad to the rear of the type-head after the type is inked.

The clutch mechanism for throwing the printing and inking mechanisms in and out of connection with the driving mechanism consists of the following means: The bracket m' , rigidly secured to shaft E, is provided with an arm m^3 and a short rod m^4 , extending at a right angle from said arm, and on this rod is hung a clutch-pawl O, having at one end a toe o^1 and at its opposite or heel end a clutch-pawl o^2 . On the side of the heel the clutch-pawl has a pin o^3 , with which engages the end of a spring o^4 , said spring being extended back and coiled upon rod m^4 on the bracket-arm and its extreme end secured to a smaller pin on said arm. The action of said spring is to hold the tooth of the clutch-pawl into engagement with a cog F' within the face of the larger cog F and rigidly secured to or 115 cast on the hub of the latter, whereby when the machine is in operation all the type-operating parts are in gear with the motive power and work together.

P is a rocking lever-bar centrally pivoted 120 on rod p . One end p' of the bar extends under and is adapted to be pressed down by the platen when the latter is lowered and to be forced up and the opposite end depressed by the action of a spring p^2 , secured to the 125 under side of the frame of the machine and bearing against the bar. The inner end of the bar is provided with a tooth, against which the end of the clutch-pawl opposite the tooth is adapted to strike in its revolution when the platen is depressed and the inner end of the bar up, the pressure of the bar against this end of the clutch-pawl serving to raise the tooth from engagement with

the cog-wheel, and thus disconnect the gearing with the cam-shaft. When the end of the bar is carried down by its spring, then the tooth of the clutch-pawl again engages the cog-wheel and the printing and driving mechanisms are connected. To raise the platen, the latter is secured to the top of a hollow standard R and the latter connected to a cap r^4 on a rod r' by a set-screw, which rod 10 in turn is connected to a treadle S. The standard R slides freely through a sleeve R^4 , extending down from the base of the machine. The base of the platen is also provided with a steady-pin s' , which slides vertically in the 15 frame.

The standard R is internally provided with a coiled spring R^2 and a supporting-rod r^3 within the coil for the purpose of affording a yielding action to the platen under the force 20 of the blows of the type-head and to afford to the platen a self adjusting or compensating action to accommodate it to the use of a greater or less thickness of the article or layers of articles to be imprinted. The platen 25 is also provided with an adjustable spring-clamp S³ to hold the articles to be stamped on the platen in front of the type-head and readily adjustable to many variations in the dimensions thereof. It is composed of a 30 casing, which is screwed to the under side of the platen, a series of screw-holes being provided through the top of the platen, as shown, whereby it may be adjusted in and out to accommodate various sizes of articles 35 to be stamped, and has a clamp-finger and thumb-piece s^5 , pivoted to the casing, the heel of the clamp resting against the free end of a spring-bar s^6 , secured within the casing. The action of the spring is to automatically 40 hold the sheets or layers of articles as they are increased or diminished in thickness, and its employment permits the free use of both hands for other purposes. The platen is also provided with a cushion s' , fixed on the 45 platen directly beneath the type-head to resist the rigidity and force of blows and to thus preserve the face of the type. We regard this as possessing an advantage over those stamps having the cushion in the plunger-head, as it is a more simple and effective 50 arrangement, in that it obviates any special construction of the plunger-head for the purpose and permits the types to be given a more positive compression, while at the same time 55 it cushions the blow, relieving the types from impact with a solid body. It also to some extent yields to irregular surfaces of some articles to be stamped, thus producing a more perfect imprint.

60 Y is an adjustable gage for the work, secured by a thumb-screw to the frame of the machine and to the rear of the type-head to gage the distance from the edge of the article to the place of the imprint thereon.

65 The type-head B is provided with a series of ring type-disks t , mounted loosely on a central hollow shaft T. One end of this shaft

outside the head terminates in a knob t^2 for turning the shaft and for the consequent turning of the disks separately. Each disk 70 is provided on its periphery with raised letters, figures, or other characters t^3 . Between the raised characters each disk is provided with index characters t^4 , flush with or below the surface of the disk. A single disk used 75 for the purpose hereinafter described is provided with merely a single index character and a corresponding printing character and plain raised portions and recesses on the rest of its periphery. Each disk, except the one 80 last referred to, is also provided with four interior slots t^6 , cut through its edge, encircling the shaft T. The purposes of these various features of the disks are hereinafter described. At the back of the type-head and hung on 85 a single rod so as to turn loosely thereon are a series of spring-pawls t^5 , one pawl for each disk. The form of these pawls is shown in detail in Fig. 8. These pawls extend down under the type-disks and engage therewith 90 at their lower sides. Each pawl is provided with a spring-rod t^7 , which projects above the edge of the type-head. Washers are hung on the pawl-supporting rod between the pawls to permit the free and independent movement of the latter. One disk t^8 is unprovided 95 with the interior slots, having a plain inner periphery. This disk carries the character “½” in index and printing type. Secured to this disk is a lever U adapted to rotate the 100 disk on its shaft. A spiral spring t^9 connects a projection from the disk t^8 with a rod of one of the spring-pawls. The pawl of the disk adjacent to disk t^8 has a pin u^4 , engaging an elongated aperture in the pawl of the latter 105 disk, so that when the adjacent pawl is pressed back by its disk the pawl of disk t^8 will also be carried back and out of engagement with said disk. The pawl t^{10} corresponding to the disk t^8 is made shorter than 110 the other pawls and is provided with a single abrupt projecting tooth at the end to engage the disk, the middle projection found in the other pawls being dispensed with, whereby the disk t^8 is held firmly from being drawn 115 backward by its retracting-spring t^9 when one of its teeth has engaged the pawl-tooth and the disk is held in position for printing.

U' is the top or cover of the type-head and is provided on its under surface with a rod u , 120 which when the cover is screwed in place bears against and presses back the spring-pawl rods, thus forcing the pawls into engagement with the disks. The top is slotted to allow the lever U to pass through and be 125 moved to and fro, while at its rear end it is provided with a projection having a pin on which slides a slotted lever U^2 . This lever slides in a slot in the cover and is provided with a pin u' to keep it therein. It also has 130 a tooth u^2 at its front part to engage the teeth of the disk adjacent to the disk t^8 and having the pawl provided with pin u^4 . Attached to the lever U^2 is a curved spring u^3 , the rear

end of which bears against the link-journals of the type-head and forces the lever out to the end of the slot. The tooth of each pawl rests normally in the recess or space between two raised characters.

V is a sliding barrel placed within the shaft T. It is given its sliding movement by means of a handle V', which is secured to the barrel by means of a screw v². The screw v² passes 10 into the outer end of a rod v³, and the rod is held in place in the barrel by a collar v⁴, engaging with a lug in the inner end of said rod. A sleeve surrounds the rod between the end of the barrel and a collar of the rod 15 on its outer end. The handle V' is provided with a pointer g⁸. The barrel near the end opposite to that on which the handle is hung is provided with a slot v⁶. In this slot is placed a detent v⁸, (shown in detail in Fig. 9,) having at one end a tooth v⁹ and at the opposite end a small curved cross-head v¹⁰. A flat downwardly-extending spring v¹¹ is secured to the under side of the detent and bears 20 against the bottom of the slot. The tooth of the detent protrudes above the surface of the barrel through the slot v⁶, and the cross-head rests in a cross-groove and is flush with the surface of the barrel, being held in its seat by the wall of the hollow shaft T. The 25 detent-tooth is exactly opposite the pointer, and hence engages the same disk to which the pointer points. The shaft T is provided with a longitudinal slot t², which registers with the slot in the inclosed barrel and 30 through which the tooth of the spring-pressed detent also protrudes. The object of the detent is to engage with the nearest slot in a type-disk and to rotate it when the barrel and disk-shaft are rotated by the knob. It is not 35 necessary that the slots in the several disks should register for this purpose, and the disks may be provided with as many slots as is desired for convenience and rapid work. Four slots being a convenient number, the disks 40 are illustrated with that many, but they may have one or more. The relative positions of the various parts above described in connection with the type-disks are shown in Figs. 5, 6, and 11.

50 There is a modification of both the type-disks and their operation and of the adjusting means for the platen, but before their description the operation of the above arrangements will be given.

55 Let it be assumed that the following characters are to be stamped on a shoe-lining: "10 $\frac{1}{2}$ E—57678." Before beginning the operation the type-disks are held from turning by their spring-pawls. The pointer g⁸ is set 60 opposite a disk having an index-figure "1" and raised figure "1" upon it. In the arrangement mentioned this is the first disk next to the knob. The placing of the pointer in this position will also carry the detent to the same disk. The disk-shaft, by means of the thumb-nut, is then rotated, carrying the detent-barrel with it until the tooth of the spring-pressed

detent engages a slot in the disk, whereupon the detent rotates the disk as the turning continues. The turning is continued until the index-figure "1" is under the pointer. When the first index-figure is thus properly placed, the corresponding raised figure 1 will be in a proper position at the bottom of the type-head to be stamped. The pointer is then 70 slid back to the next disk, carrying back the barrel and the detent to that disk, when the above operation is repeated until the figure "0" is reached and set in place. When the barrel is drawn along under the smooth portions of the peripheries of the disks, the detent will be pressed down into the slot. To bring the character " $\frac{1}{2}$ " into printing position, the lever U is moved forward to the end of its slot, which turns the disk t⁸, carrying 75 the index character to the front and the type to its printing position at the bottom of the type-head, in which position the disk will be firmly held by the abrupt tooth of its engaging-pawl. The remaining characters are 80 adjusted as described in the case of the first two numerals. To restore the disk t⁸ with the " $\frac{1}{2}$ " character to its normal position, the lever U², having the tooth adapted to engage the disk adjacent to the disk t⁸, is moved back, 85 which carries back its engaging-disk. The pawl of this disk is thus forced back, and by means of its pin u⁴ engaging the apertured pawl t¹⁰ forces back the latter pawl and releases the tooth of the same from engagement 90 with disk t⁸, which is thereupon automatically retracted by the spiral spring t⁹. The aperture of pawl t¹⁰ is elongated to permit of the free movement therein of the pin u⁴ of the adjacent pawl when it is desired to independently adjust the disk of the said adjacent 95 pawl. The character " $\frac{1}{2}$ " is mounted on a disk of different style from the other characters and provided with a separate setting device, because it is the character most frequently used, and the separate disk and setting means therefor permit it to be set in co-operation with any other character with rapidity and convenience and without necessitating the careful rotation and adjustment 100 of a disk bearing several characters.

A modification of the type-head disks and the pointer is illustrated in Figs. 13 and 15. Instead of arranging the index characters on the peripheries of the disks they are placed 105 in circular rows on and around the surface of the knob t², employed, as already described, to rotate the disk-shaft and detent-barrel. In this arrangement an additional pointer n is employed, fixed to the frame above the 110 knob. The other pointer on the detent-barrel handle is now employed only to indicate the proper disk having the raised characters to be used; but of course the detent is carried with it to that disk, as before. The index characters on the knob are arranged in 115 circular rows, each corresponding to one of the circular sets of characters on the respective disks. The index character on the knob 120

directly under the pointer indicates the disk character in position for printing. Since each index character in each row is in fixed relation with the same character on the corresponding disk, it is clear that if there were several slots in the disk the latter might be turned to a different printing character than that under the knob-pointer. Therefore in setting a character or row of characters by the respective pointers there must be but one slot formed in each disk, so that when the pointer over the knob and the detent and detent-pointer are set to the same character on a particular disk the tooth of the detent must register with and enter the slot in the disk in order to rotate the disk and bring that character to its proper position at the bottom of the type-head for printing.

In operating the modification let it be supposed that the character A is desired to be set and printed. The detent-pointer is slid first to the disk having that character, thus carrying the detent to that disk, and then the knob is turned until the same character appears thereon under the pointer on the frame, whereupon the corresponding printing character will be turned to the proper position at the bottom of the disk, and the same operation is continued with the other characters desired to be printed.

A modification of means for automatically adjusting the platen and engaging the machine with the clutch, and thereby dispensing with the treadle and spring in a standard below the platen, is shown in Fig. 10. It consists of a spring Q, coiled around the same standard R (or another shorter standard may be employed) and confined between the frame and the bottom of the platen, as shown in the same figure, and in the employment of a flexible wire rod p', connected to the end p' of the lever-bar P'. The lower end of the wire rod may be connected to any suitable footpiece or treadle. The normal action of the spring Q will be to hold the platen up; but it renders the platen elastic and self-adjusting, as in the other form. It constitutes only a somewhat more simple means than the other device.

The operation of the whole machine is as follows: The driving mechanism being set in motion by connection of the pulley-wheel with suitable power, the type to print the characters desired are set in the manner hereinbefore described and the double arm to which are attached the swinging links of the inking-pad adjusted to the required throw. The platen is then raised by pressure on the treadle, and the outer end of arm P being released from the pressure of the platen is forced up by its spring, raising the opposite end of the bar. The inner end of the bar normally contacts with the heel of the clutch-plate and prevents its engagement with the cog-wheel of the driving mechanism; but when such contact is removed by the lower-

ing of the end of the bar the clutch again engages the cogs, and the shaft on which the clutch is mounted is turned by such engagement. Rotating this shaft turns the cams mounted thereon, the large cam reciprocating the type-head arm up and down and printing on the articles clamped on the platen at each stroke, while the smaller cam intermittently throws the pad forward to ink the type just before the descent of the arm. When it is desired to reset the type characters or to replace the articles stamped with a new supply, the platen is lowered, whereby the printing and driving mechanisms are disconnected, the latter, however, continuing in motion.

Having thus described our invention, what we claim is—

1. In a stamping and numbering machine, the combination of a plunging type-carrier, with independently-adjustable type, a continuously-operating driving mechanism and means to connect and disconnect said driving means and type-carrier, substantially as described.

2. In a stamping and numbering machine, the combination with a plunging type-carrier, of a continuously-operating driving mechanism, independently-adjustable type, a single handle for adjusting or setting said type, and means to connect and disconnect said driving means and type-carrier, substantially as described.

3. In a machine of the class described, in combination with a suitable frame, printing characters and their holder, a rocking lever-arm having a short arm and a long arm, said long arm carrying at its end said characters and holder, a cam engaging the end of said short arm, a shaft carrying the cam, and driving means connected with said shaft, whereby when said short arm reaches the reduced portion of said cam, the long arm and characters-holder will be thrown forcibly downward by their own weight and an intermittent plunging movement given thereto, substantially as described.

4. In combination with a swinging type-head, a platen to receive the impressions of said type-head, a vertically-adjustable standard supporting said platen, a spring for giving said platen and standard an automatic self-adjustment in either position of said standard, a driving mechanism, a clutch intermediate said type-head and driving mechanism and connections between said platen and clutch, whereby the vertical adjustment of the platen will control the operation of the clutch, substantially as described.

5. In a machine of the class described, in combination with type-disks rotatable in either direction, a type-head, a shaft on which said disks are mounted, means for separately setting said disks independently in printing position, and a presser member for each disk for holding it in position and yielding to the

pressure of the disk when the latter is turned by the setting means, substantially as described.

6. In a stamping and numbering machine, in combination with a vibrating type-carrier, a series of type-disks, said disks having raised printing characters and recesses formed between said characters, a rotatable setting-shaft on which the disks are loosely mounted, 10 a thumb-piece for turning said shaft, a sliding detent in said shaft, interior recesses in said disks with which said detent is adapted to engage, a separate spring-pressed retaining-pawl for each disk, the tooth of said pawl having double ends and adapted to engage 15 the exterior recesses of the disk, whereby when the disk is turned by the shaft the pawl-tooth will ride over the characters and when the disk is at rest will be forced into the recesses to hold the disk in place, substantially as described.

7. In a stamping and numbering machine, in combination with a vibrating type-carrier, a series of type-disks, a hollow shaft on which 25 they are mounted a rotatable and longitudinally-sliding barrel within said shaft, a spring-pressed detent in said barrel, means of engagement between said detent and disks, a rod on which said barrel is rotatably carried, 30 a pointer secured to said rod and extending over the disks, yielding pressure means for holding the disks against loose movement, substantially as described.

8. The type-head and its carrying-arm, in 35 combination with the inking-pad and an extensible carrying-arm therefor, connections between said arms and means for lengthening and shortening said pad-arm to adjust it to and from the type characters and in line 40 with the type-head-carrying arm, substantially as described.

9. In combination with a platen, a rocking lever-bar, a drive-gear, a spring-controlled clutch-pawl held on said gear and with which 45 pawl said lever-bar is adapted to engage, the operating-shaft to which said clutch is connected, means of connection between the lever-bar and the platen and means for raising said platen, whereby when the platen is raised 50 the said rocking lever will be released from the clutch-pawl and the driving and printing mechanisms connected, substantially as described.

10. In combination with a gear-wheel, a 55 spring-pressed clutch-pawl adapted to engage said wheel, a rocking lever adapted to engage said clutch to effect the disengagement of said clutch and gear-wheel, means to rock said lever, a continuously-operating driving mechanism connected with said gear-wheel, a printing mechanism, said clutch adapted to connect said driving and printing mechanisms, substantially as described.

11. The swinging and reciprocating inking- 65 pad and its carrying-arm in combination with the plunging arm of the type-head, and the pivoted links connecting the said arm of the

type-head and the arm of the pad, a shaft, cams on said shaft to engage said plunging arm and type-head and driving means engaging said shaft to rotate the same, substantially as described. 70

12. In combination with the slotted shaft, disks mounted loosely on said shaft and provided with printing characters on their peripheries, a pointer to indicate said character-disks, a knob to turn said shaft, said knob provided with index characters denoting the same characters as are on said disks, a pointer on the machine over said knob, each of 80 said disks provided with a single interior slot, a barrel sliding in said shaft, said barrel provided with a spring-pressed detent engaging the slot in the said shaft and the slot in the disk, whereby on turning the knob to a certain index character, a disk will be turned to present the same character for printing, substantially as described. 85

13. In combination with type-disks, spring-pressed pawls engaging therewith, means of 90 engagement between two adjacent pawls, said other pawls independent of each other, substantially as described.

14. In combination with type-disks and their support, means to adjust said disks, one 95 of said disks provided with a single type and an adjusting-lever secured to said disk and independent of said other adjusting means, substantially as described.

15. The combination with a type-disk, of a 100 spring-pressed pawl engaging therewith, a lever secured to said disk, a spring connected with said lever, and means to effect the disengagement of said disk and pawl, substantially as described. 105

16. In combination with a type-disk, provided with a single type, a spring-pressed pawl engaging therewith, means for giving said disk a limited rotation, an adjacent disk and its pawl, means of engagement between the two pawls, a sliding lever mounted in the frame of the machine and adapted to engage said latter disk, and spring secured to said lever, substantially as described.

17. The combination of the type-disks having the raised printing characters and the spaces between said characters, with the detaining-pawls adapted to engage said disks, spring-rods secured to said pawls, means to bring pressure on said rods, a rotatable setting-shaft on which said disks are mounted and means for engaging one of said disks with said shaft, substantially as described. 115

18. The type-head in combination with the type-disks and type thereon, the pawls engaging said disks at the bottom of the head, spring-rods secured to said pawls, the removable cover for said head, a bar secured to said cover and adapted to press against said pins, substantially as described. 125

19. The combination of the type-head and its pivoted arm, the inking-pad and its arm, the latter pivoted at its rear part to said type-head arm and having its front part pivotally 130

connected by swinging links thereto, the gear-wheel, the shaft on which said gear-wheel is mounted, a cam-wheel on said shaft and cam carried thereby to engage the type-head arm, 5 and the cam mounted on said shaft to engage the pivoted pad-arm, motive power and connections between said motive power and the gear-wheel, substantially as described.

In testimony whereof we hereunto affix our signatures in the presence of two witnesses. 10

JAMES D. HUMPHREY.
